UNITED STATES PATENT OFFICE.

WILLIAM O. PIERCE, OF PLACERVILLE, CALIFORNIA.

NECKTIE.

No. 833,083.

Specification of Letters Patent.

Patented Oct. 9, 1906.

Application filed January 2, 1906. Serial No. 294,262.

To all whom it may concern:

Be it known that I, WILLIAM O. PIERCE, a citizen of the United States, residing at Placerville, in the county of Eldorado and State of California, have invented certain new and useful Improvements in Collars and Combination-Ties; and I do hereby declare the following to be a full, clear, and exact description of the invention, such as will enable others skilled in the art to which it appertains to make and use the same.

This invention relates to improvements in neckwear, and has for its object to provide a collar which, owing to its construction will assist in taking off the pressure from the neck of the rear collar-button of a shirt.

Another feature of the invention is to provide a tie attachment, in combination with the collar, whereby the tie will be held against the collar and in cases of its use with roll-collars will be prevented from binding between the folds of the collar, the aim being to do away with the usual friction caused by the pressure of the folds against the inclosed tie.

While it is to be understood that the invention is not limited to the specific details as disclosed, for the purpose of illustration in the accompanying drawings I have illustrated a practical embodiment of the invention, the novel features of which will be more specifically pointed out in the claim.

Referring to the drawings, Figure 1 shows the improved tie applied in position between the folds of a turn-down collar; and Fig. 2 is a plan view of the interior of a turn-down collar, the folds being laid back and the tie shown in operative relation therewith.

1 designates the outer and 2 the inner fold of a turn-down collar having the usual end buttonholes 3 and central buttonhole 4.

In all collars when a tie is secured thereto around there is more or less of a tendency to press the collar inwardly against the neck, and consequently there is a pressure of the button on the spinal bone. This is often-times attempted to be overcome by placing the back of the button between the neckband proper of the shirt and a flap, so that the button itself does not bear directly on the neck. In the collar as I construct it, however, the tendency of the button to press on the neck is obviated by means of a nib or

flap 5, secured to the lower edge of the collar adjacent the central buttonhole. This nib 55 is provided with a buttonhole 6, which is secured to the shirt below the neckband and prevents the collar from pressing inwardly. In use the nib 5 is not starched, which renders it easier to button and less apt to become unbuttoned.

7 designates the ends of a string, bow, or four-in-hand tie comprising two sections intermediate secured by means of an inextensibly rigid but flexible strip 8 of any suitable material, but preferably of whalebone or band of thin steel. In the drawings this flexible strip 8 is composed of a metallic band having looped ends 8^a, adapted to engage apertures formed in metallic ears 9, secured to the ends 7 of the tie. By this means the flexible strip is readily detachable from the tie ends to permit of the tie being detached from the collar, and, if desirable, sliding loops 10 may be employed to engage over 75 the bent ends 8^a and hold the free ends in intimate contact with the strip 8.

The collar is provided with loops 11 in any suitable manner, and through these loops is adapted to be passed the flexible strip 8. By 80 this construction it will be seen that not only is the length of the tie diminished, and hence a lesser quantity of material necessary, but also there is provided means whereby the friction between the collar and tie is reduced 85 to a minimum. An additional advantage is obtained by this construction, inasmuch as the loops hold the tie in position on the collar, so that after the wearer has taken the collar off he may put it on again without the inconvenience of readjusting the tie with respect to the collar.

What I claim is—

A tie composed of two end members and an intermediate member detachably connecting said end members, said intermediate member being formed of an inextensibly rigid but laterally-flexible material and adapted to be operatively associated with a collar, substantially as described.

In testimony whereof I affix my signature in presence of two witnesses.

WILLIAM O. PIERCE.
